TOOL

John Kopeczynski, Buffalo, N. Y.

Application February 19, 1943, Serial No. 476,455

19 Claims. (Cl. 164—124)

This invention relates to tools and particularly to means for holding replaceable tool elements in operative positions in a body or tool holder.

An example of such tools is found in the punching art, where one or more punches are secured by their shanks in a head or holder and each operated into and out of a punching die, so that when a sheet of material is disposed over a punching die and the punch is caused to pierce the sheet and enter the punching die, a slug will be punched from the sheet. When the punch is withdrawn, a suitable stripper beneath which the sheet has been disposed will strip the sheet from the punch. When such punches break, their replacement has been relatively slow, with substantial loss of production time. Various constructions have been proposed to facilitate the replacement of broken punches or tools, but such constructions heretofore have not been entirely satisfactory for various reasons, such as their relatively high cost, difficulty in their manufacture, their relatively complex construction, and the time required to replace a broken punch or tool element.

An object of this invention is to provide an improved and simple support or mounting for a tool element, such as a punch for a punch press, which will require a minimum of departure or changes in the constructions of devices of the same types heretofore in use; which will not greatly increase the cost of manufacture of the same; with which a punch or tool element may be quickly and easily replaced, in the event of breakage or when renewal is desired, or when setting up for new work; with which the tool element will be accurately positioned and effectively secured at all times, and which will be relatively simple, practical and inexpensive.

Other objects and advantages will appear from the following description of an embodiment of the invention, and the novel features will be particularly pointed out hereinafter in connection with the appended claims.

In the accompanying drawing:

Fig. 1 is a sectional elevation through a portion of a punch press having incorporated therein a mounting of a tool element in accordance with this invention, the punch being in depressed or operated position;

Fig. 2 is a sectional plan of the same with the section taken approximately along the line 2—2 of Fig. 1;

Fig. 3 is a side elevation of part of the punch press shown in Figs. 1 and 2, with the punch depressed; and

Fig. 4 is a sectional plan of the same, similar to a portion of Fig. 2, but with the tool element rotated into a position in which it may be withdrawn for replacement.

5 In the illustrated embodiment of the invention, the particular tool is a punch press which includes a suitable base 10 having a slug passage 11 therethrough, and in its upper face and at the upper end of and aligned with the slug passage 11, 10 a suitable die 12 with a die opening 13. The usual stripper plate 14 may be secured to the base 10 so as to extend over and be spaced from the die 12. This stripper plate 14 is provided with an aperture 15 through which the working 15 end of a punch or tool element 16 extends, and in which it reciprocates in the operation of the punch press. The shank or head of this tool element 16, which in this example is a punch, is releasably secured in a head 17 formed of a plurality of sections 18, 19 and 20 abutting sequentially face to face. Heretofore the sections 19 and 20 have been made of a single piece or body, but in accordance with this invention, they are made of separate pieces abutting face to face and secured together in that relation in any suitable manner.

25 These sections 19 and 20 are provided with passages 21 and 22 aligned end to end, which together form a recess opening upwardly in the lower face of the section 20. This recess is of a size and shape to rotatably and slidably receive the head or shank of the punch 16 or other tool element. One of the sections 19 and 20, such as the section 19, is provided on the face which abuts the other 30 section, such as the section 20, with a shallow cavity 23, see Figs. 2 and 4, which cavity intersects to some extent the recess formed of the aligned passages 21 and 22, as shown in Figs. 2 and 4. This cavity 23 is of uniform depth and is closed by the abutting face of the section 20. Within this cavity 23 is a flat, plate-like key 24 which has a uniform thickness only slightly less than the depth of the cavity 23, and slides back and forth freely in the cavity into and out of a 35 position partially across the recess formed of the passages 21 and 22.

40 The shank or end of the punch or other tool element which is received within the passages 21 and 22 is preferably cylindrical and provided with a transversely extending kerf or milled slot 25 which corresponds in size and shape to a removed segment of a cylinder. The width of this 45 kerf or slot 25 is slightly greater than the thickness of the key or plate 24, and when the tool element is inserted in the passages 21 and 22, into 50 55

the position shown in Fig. 1, this kerf or slot 25 will be placed in alignment with the key 24, and the latter may then move into the kerf or slot to anchor the tool element against removal from the passages 21 and 22. The opposed side walls of the slot 25 are substantially parallel to each other and in planes approximately normal to the longitudinal axis of the tool element.

A spring 26 is disposed in the cavity 23 under compression between an edge of the key 24 and the rear of the cavity, and it yieldingly and continuously urges the key 24 in a direction toward the passages 21 and 22, and thus into the kerf or slot 25 in the tool element when the latter is inserted into the passages 21 and 22 with kerf in the portion abutting the cavity 23. The depth of the kerf or slot 25 may be approximately equal to the extent to which the cavity 23 intersects the passages 21 and 22, as shown in Fig. 2. In Fig. 1, considerable clearance is shown between the faces of the key 24 and the sides of the kerf or slot 25, but this is done for the purpose of illustrating clearly the principle of the invention, and it will be understood, in practice, that such clearance will be relatively small, and especially that clearance between the upper side of the kerf or slot 25 and the upper face of the key 24, should be just sufficient to allow the key 24 to be freely snapped into the slot or kerf 25 when the tool element is inserted fully into the recess formed of passages 21 and 22.

To facilitate the insertion of the tool element into the head, the upper end face of the tool element, at the corner or edge aligned vertically with the kerf or slot 25 may be bevelled as at 27, so that when the tool element is inserted into the passage 21, with the bevelled corner 27 aligned with the key 24, the inward or upward movement of the tool element into the passage 22 will cause the bevelled corner 27 to cam aside the key 24, during which the spring 26 is compressed, and then when the kerf or slot 25 moves into alignment with the key 24, the latter will snap into locking position therein, and effectively hold the tool element within the head. The key provides sufficient strength to retain the tool element in the head, even though a heavy downward pull may be exerted on the tool element during its elevation while the sheet is being stripped therefrom by the stripper plate 14.

In the event of breakage of the tool element, or if one desires to change the tool element for a different job, it is merely necessary to rotate slightly the tool element in the aligned passages 21 and 22, and the cylindrical surface of the shank or head of the tool element within the passage 22 at either end of the kerf or slit will act as a cam to cam or force the key 24 back into the cavity 23, as shown in Fig. 4, sufficiently to completely disengage the key 24 from the kerf or slot 25. The tool element may then be pulled downwardly by a simple endwise movement which fully releases it from the head. The 24 then snaps back into the position shown in Fig. 2, except that the tool element has then been withdrawn.

To insert a new element, that element is moved upwardly in the passage 21 with the bevelled corner 27 aligned vertically with the key 24, and during this upward movement, the corner 27 cams the key aside, and then the key snaps into the kerf or slot 25 of the new tool as soon as the slot moves into alignment therewith. Thus, a tool element or punch may be quickly and easily replaced for any reason, merely by first rotating the tool element or punch through a part of a

revolution to cam the key 24 into retracted position, as shown in Fig. 4, and thereupon endwise movement of the tool element will release. A new tool may be then reapplied, merely by a simple upward movement of the tool element into the aligned passages 21 and 22. It will be noted that very few changes in existing constructions are necessary and that the major changes over prior devices are in cutting the kerf or slot in the head or shank of the tool which is received within the head of the press, beveling the end face of the tool at the corner edge thereof which is in vertical alignment with the kerf or slot, providing two sections 19, 20, milling or forming the cavity 23 in a face of one of the sections 19 and 20, forming the key 24 from a simple flat plate, and in adding a simple spring 26. The cost of the device is thus very low, the change is easily made in existing types of devices, and the tool elements may be quickly and easily changed in a minimum amount of time with a minimum of movements, and with no special tools usually required. If the punch binds in its mounting, pliers or other tools may be applied to the punch or tool element to turn it and to move it endwise.

It will, of course, be understood that while the invention has been illustrated and described in connection with quick change dies and punches, the same idea may be similarly employed in securing other tool elements in operative positions in holders where similar problems are encountered.

It will be noted that the cavity 23 is clear or free of all positive mechanical obstructions to the free back and forth movement of the key into and out of a position in the transverse slot in the tool element. The key moves in a plane normal to the longitudinal axis of the recess in which the tool element is received, so that there will be no unnecessary binding or wedging of the key that would interfere with its spring action. The side wall of the slot 25, which is the upper one in Fig. 1, and the face of the key 24 that is engaged by that wall are both in planes normal to the longitudinal axis of the recess in the holder, so that danger of the key being unintentionally released by a cam action between the slot wall and the key is avoided. The cavity 23 is of simple form so that it can be milled out easily. It will also be noted that the key is unbroken from end to end entirely through the slot 25, thus giving maximum strength. Since the cavity 23 is shallow, it does not materially weaken the holder section in which it is formed.

It will be also understood that various changes in the details and arrangements of parts, which have been herein described and illustrated in order to explain the nature of the invention, may be made by those skilled in the art within the principle and scope of the invention as expressed in the appended claims.

I claim as my invention:

1. A tool comprising a holder formed of two sections abutting face to face and having passages aligned end to end to form a recess extending through one section into the other, with its longitudinal axis normal to said faces, one of said sections having a cavity in that face thereof which abuts the other section and intersecting said recess, a tool element rotatable and slidable endwise in said recess and having a segmental kerf in a side thereof which may be aligned with and opening into said recess when said element is fully within said recess, a key confined within and slidable in said cavity, into and out of said kerf, a spring in said cavity urging said key yieldingly

into said kerf, a peripheral zone of said element leaving an end of said kerf being circular to fit the abutting circular wall of said recess, whereby when said element is rotated about its longitudinal axis, while fully within said recess, in a direction to carry said zone thereof against said key, it will said key back in said cavity and out of said kerf to release said element, the entering end face of said element being beveled on an edge to cam aside said key and allow full entry of said element into said recess when said element is pushed endwise into said recess with said beveled edge aligned with the side of said recess intersected by said cavity.

2. A tool comprising a holder formed of two sections abutting face to face and having passages aligned end to end to form a recess extending through one section into the other, with its longitudinal axis normal to said abutting faces, one of said faces having therein a cavity intersecting said recess, a flat key having parallel faces and slideable in said cavity between one position in which it lies partially across said recess and another position in which it is clear of said recess, and means for yieldingly and continuously urging said key into its said one position, whereby when the shank of a tool element with a transverse kerf therein is inserted in said recess with said kerf aligned with said cavity, said key may be projected into said kerf to lock said tool element against removal from said recess.

3. A tool comprising a holder formed of two sections abutting face to face and having passages aligned end to end to form a recess extending through one section into the other, with its longitudinal axis normal to said abutting faces, one of said faces having therein a cavity intersecting said recess, a flat key having parallel faces and shiftable in said cavity between one position in which it lies partially across said recess and another position in which it is clear of said recess, means for yieldingly and continuously urging said key into its said one position, and a tool element having a shank removably insertable endwise in said recess and slideable endwise and rotatable therein, said shank having a transverse kerf aligned with said cavity when said element is fully within said recess, and into which said key may be moved by said urging means to lock said element within said recess, said kerf having its side wall nearest the end first entering said recess, disposed approximately normal to the longitudinal axis of said recess.

4. A tool comprising a holder formed of two sections abutting face to face and having passages aligned end to end to form a recess extending through one section into the other, with its longitudinal axis normal to said abutting faces, one of said faces having therein a cavity intersecting said recess, a flat key having parallel faces and shiftable in said cavity between one position in which it lies partially across said recess and another position in which it is clear of said recess, means for yieldingly and continuously urging said key into its said one position, and a tool element having a cylindrical shank fitting and movable endwise into and out of said recess and also rotatable within said recess about its longitudinal axis, said shank having a transverse kerf across a portion of its side and aligned with said cavity when said element is fully within said recess, the planes of the opposite side walls of said kerf being approximately normal to the axis of said recess and spaced apart to receive between them said key.

5. A tool comprising a holder formed of two sections abutting face to face and having passages aligned end to end to form a recess extending through one section into the other, with its longitudinal axis normal to said abutting faces, one of said faces having therein a cavity intersecting said recess, a flat key having parallel faces and shiftable in said cavity between one position in which it lies partially across said recess and another position in which it is clear of said recess, means for yieldingly and continuously urging said key into its said one position, and a tool element having a shank removably insertable endwise in said recess and slideable endwise and rotatable therein, said shank having a transverse kerf aligned with said cavity when said element is fully within said recess, and into which said key may be moved by said urging means, to lock said element within said recess, said kerf having its side wall nearest the end first entering said recess, disposed approximately normal to the longitudinal axis of said recess, the end face of said element first to enter said recess being beveled on an edge to act as a cam and push aside said key as said element is inserted endwise into said recess with said beveled edge aligned, in a direction lengthwise of said recess, with the portion of said key extending into said recess.
6. A tool comprising a holder having a cylindrical recess, a tool element having a cylindrical shank received in said recess and movable endwise and rotatably therein, said shank having a transverse kerf cut segmentally across a side thereof in the portion within said recess, the side wall of said kerf first entering said recess being a flat surface and in a plane substantially normal to the longitudinal axis of said recess, said holder also having entirely enclosed therein, a shallow, closed cavity which along one side edge thereof slightly intersects said recess, a flat plate-like key disposed in said cavity and movable rectilinearly therein in a direction radially towards and from said axis of said recess to move an edge portion thereof into and out of a position across a portion of said recess, said key having a thickness at its said edge portion that enables that edge portion to enter said kerf, and a flat face and a flat zone along said edge portion on the face of the key abutting said flat side wall of said kerf, which flat zone is in a plane normal to said recess axis, and a spring within said cavity and compressed between an edge of said key and an edge wall of said cavity and yieldingly urging said key into said kerf to latch said shank within said recess.
7. A tool comprising a holder formed of a plurality of flat plates abutting face to face sequentially and having a cylindrical recess extending in a direction normal to said abutting faces, a tool element having a cylindrical shank received in said recess and movable endwise and rotatably therein, said shank having a transverse kerf extending segmentally across a side thereof in the portion within said recess, the opposite side walls of said kerf being approximately flat and parallel to each other and in planes approximately normal to the longitudinal axis of said recess, said holder also having entirely therein between two of said abutting faces, a shallow, closed cavity of uniform depth and slightly intersecting said recess, at one side thereof, a flat key disposed in said cavity and movable therein into and out of a position across a portion of said recess and having, along its side edge nearest said recess, flat, parallel faces defining a thickness that enables said side edge portion of said

key to enter said kerf, and a spring within said cavity and compressed between an edge of said key and an edge wall of said cavity and yieldingly urging said key into said kerf to latch said shank within said recess.

8. A tool comprising a holder formed of a plurality of flat plates abutting face to face sequentially and having a cylindrical recess extending in a direction normal to said abutting faces from one face only of said holder and past one of said abutting faces, a tool element having a cylindrical shank received in said recess and movable endwise and rotatably therein, said shank having a transverse kerf extending segmentally entirely across a side thereof in the portion within said recess, the side wall of said kerf first to enter said recess being in a plane substantially normal to the longitudinal axis of said recess, said holder also having entirely therein and between two of said abutting faces, a shallow, closed cavity slightly intersecting said recess at one side thereof, a flat plate-like key disposed in said cavity and movable rectilinearly therein into and out of a position across a portion of said recess to move an edge zone thereof into and out of the face of said key farthest from the entrance to said recess and along said zone being flat and in a plane normal to said recess axis, and a spring within said cavity and compressed between an edge of said key and an edge wall of said cavity and yieldingly urging said key into said kerf to latch said shank within said recess.

9. A tool comprising a holder formed of a plurality of flat plates abutting face to face sequentially and having a cylindrical recess opening therein from one face thereof, extending in a direction normal to said abutting faces, and also having entirely therein between two of said abutting faces a shallow, closed cavity of uniform depth and slightly intersecting said recess at one side of the latter in a zone between and spaced from the ends of said recess, a flat, plate-like key disposed in said cavity and slidable rectilinearly and bodily therein and guided at its ends by opposite sides of said cavity into and out of a position in which an edge portion thereof projects somewhat into said recess, a spring within said cavity and compressed between an edge of said key and an edge wall of said cavity for yieldingly urging said key towards said recess, whereby when a tool element is inserted endwise into said recess until a kerf on the side of said element becomes aligned with said cavity, said key may be projected into said kerf to latch said element within said recess.

10. A tool element having a shank with a channel slot extending sequentially and entirely across a side thereof at a zone spaced from the end of said shank, said slot having its opposite side walls flat, approximately parallel to each other, and in planes normal to the longitudinal axis of said shank, the end face of said shank having an edge portion thereof beveled off to serve as a cam.

11. A tool comprising a holder formed of a plurality of flat plates abutting face to face sequentially and having a cylindrical recess opening therein from one face thereof, extending in a direction normal to said abutting faces, and also having entirely therein between two of said abutting faces a shallow cavity intersecting said recess at one side of the latter in a zone between and spaced from the ends of said recess, a key confined within said cavity and shiftable rectilinearly and bodily therein in a direction ap-

proximately normal to the longitudinal axis of said recess into and out of a position in which an edge portion thereof projects somewhat into but not entirely across said recess, a spring within said cavity and under stress to urge said key yieldingly and resiliently into said position, a tool element having a shank rotatably and slidably fitting said recess and having a transverse groove extending entirely across and segmentally 10 of the periphery thereof between the ends of said recess and alined with said key when said element is fully within said recess, said groove having a distance between its opposite side walls which is greater than the thickness of the adjacent edge of said key, whereby said key when released may be automatically moved by said spring into said slot, said groove having its side wall which engages with said key to resist its removal from said recess disposed in a plane substantially 20 normal to the longitudinal axis of said recess, and said key having its face that is engaged with that wall in said groove disposed parallel to that wall, said cavity being free of positive mechanical obstructions preventing movement of said key into and out of said position.

12. A tool comprising a holder formed of a plurality of flat plates abutting face to face sequentially and having a cylindrical recess opening therein from one face thereof, extending in a direction normal to said abutting faces, and also 30 having entirely therein between two of said abutting faces a shallow cavity intersecting said recess at one side of the latter in a zone between and spaced from the ends of said recess, a key confined within said cavity and shiftable rectilinearly and bodily therein in a direction approximately normal to the longitudinal axis of said recess into and out of a position in which an edge portion thereof projects somewhat into 35 but not entirely across said recess, a coil spring within said cavity and under stress between an edge of said key and a side wall of said cavity to urge said key yieldingly and resiliently into said position, said key edge and side wall of said cavity being recessed to receive the ends of said spring, a tool element having a shank rotatably and slidably fitting said recess and having a transverse slot in and entirely across the periphery thereof between the ends of said recess and alined with 40 said key when said element is fully within said recess, said slot having a distance between its opposite side walls which is greater than the thickness of the adjacent edge of said key, whereby said key when released may be automatically moved by said spring into said slot, said slot having its side wall which engages with said key to resist its removal from said recess disposed in a plane substantially normal to the longitudinal axis of said recess, and said key having its face zone that is engaged with that wall in said slot disposed parallel to that wall, said cavity being free of positive mechanical obstructions 50 preventing movement of said key into and out of said position.

13. A tool comprising a holder having a cylindrical recess opening therein from one face thereof and also having entirely therein a shallow, closed cavity intersecting said recess at one side of the latter in a zone between and spaced from the ends of said recess, a flat, plate-like key with 55 rectangular side edges and all flat faces confined within said cavity and shiftable therein, with opposite edges thereof guided by opposite sides of said cavity and opposite faces thereof guided by 60 opposite faces of said cavity, rectilinearly in a

direction approximately normal to the longitudinal axis of said recess into and out of a position in which an edge portion thereof projects somewhat into but not entirely across said recess, a spring within said cavity and under stress to urge said key yieldingly and resiliently into said position, a tool element having a shank rotatably and slidably fitting said recess and having a transverse slot in and entirely across the periphery thereof between the ends of said recess and aligned with said key when said element is fully within said recess, said slot having a distance between its opposite side walls which is greater than the thickness of the adjacent edge of said key, whereby said key when released may be automatically moved by said spring into said slot, said slot having its side wall which engages with said key to resist its removal from said recess flat and disposed in a plane approximately normal to the longitudinal axis of said recess, and said key having its face zone that is engaged with that wall in said slot disposed parallel to that wall, also flat and in substantially continuous contact therewith entirely across said slot, said cavity being free of positive mechanical obstructions preventing movement of said key into and out of said position.

14. A tool comprising a holder formed of a plurality of flat plates abutting face to face sequentially and having a recess opening therein from an interior zone of the outside face of one of said plates at the end of a sequence and extending in a direction normal to said outside face for a distance past a pair of said abutting faces, said holder having a closed cavity and formed between said pair of abutting faces, intersecting said recess at one side of the latter, and closed around its entire periphery by said plates, a key in said cavity and movable therein into and out of a position in which it lies partially across said recess, and a spring in said cavity urging said key yieldingly into its said position, whereby when the shank of a tool element with a kerf in its side is inserted in said recess with said kerf aligned with said cavity, said key may be projected into said kerf to lock said tool element against removal from said recess.

15. A tool element having a shank extending therefrom with a channel slot extending segmentally and entirely across a side thereof at a zone well spaced from the free end of said shank, said slot having its side wall nearest said end of said shank flat and in a plane substantially normal to the longitudinal axis of said shank.

16. A tool comprising a holder formed of a plurality of flat plates abutting face to face sequentially and having a recess opening therein from an interior zone of the outside face of one of said plates at the end of a sequence and extending in a direction normal to said outside face for a distance past a pair of said abutting faces, said holder having a closed cavity of uniform, shallow depth between faces that are parallel to said abutting faces, and spaced around its entire periphery from the margins of said plates and intersecting said recess at one side of the latter, a flat plate in said cavity and movable back and forth therein into and out of a position in which it lies partially across said recess, and a spring in said recess acting between an edge of said plate and a side wall of said cavity to urge said plate towards its said position partly

across said recess, whereby when the shank of a tool element with a kerf in its side element is inserted in said recess with the kerf aligned with said cavity, said plate may be projected into said kerf to lock said tool element against removal from said recess.

17. A coupling comprising a member formed of a plurality of flat plates abutting face to face sequentially and having a cylindrical recess opening therein from an interior zone of the outside face of one of said plates at the end of a sequence and extending in a direction normal to said outside face for a distance past a pair of said abutting faces, said holder having a closed cavity formed in the interior area thereof between said pair of abutting faces and intersecting said recess at one side of the latter, a flat plate in said cavity and slidably therein and guided by the faces and sides of said cavity, into and out of a position in which it lies partially across said recess, and a spring in said cavity and acting between an edge of said plate and a side wall of said cavity to urge said plate into said position.

18. A coupling comprising a member formed of a plurality of flat plates abutting face to face sequentially and having a cylindrical recess opening therein from an interior zone of the outside face of one of said plates at the end of a sequence and extending in a direction normal to said outside face for a distance past a pair of said abutting faces, said holder having a closed cavity formed in the interior area thereof between said pair of abutting faces and intersecting said recess at one side of the latter, a flat plate in said cavity and slidably therein and guided by the faces and sides of said cavity, into and out of a position in which it lies partially across said recess, a spring in said cavity and acting between an edge of said plate and a side wall of said cavity to urge said plate into said position, and a cylindrical element rotating and sliding endwise in said recess and having in alignment with said cavity a segmental kerf cut entirely across a side of said element and of a width sufficient to receive therein the adjacent edge of said plate, the side wall of said kerf first to enter said recess being flat and in a plane normal to the longitudinal axis of said recess.

19. A coupling comprising a member formed of a plurality of flat plates abutting face to face sequentially and having a cylindrical recess opening therein from an interior zone of the outside face of one of said plates at the end of a sequence and extending in a direction normal to said outside face for a distance past a pair of said abutting faces, said holder having a closed cavity formed in the interior area thereof between said pair of abutting faces and intersecting said recess at one side of the latter, a flat plate in said cavity and slidably therein and guided by the faces and sides of said cavity, into and out of a position in which it lies partially across said recess, a spring in said cavity and acting between an edge of said plate and a side wall of said cavity to urge said plate into said position, and a cylindrical element rotating and sliding endwise in said recess and having in alignment with the cavity a notch in its side wall of a size sufficient to receive the adjustable edges and plate for normally preventing endwise movement of said element in said recess.

JOHN KOPCZYNSKI.
